REINFORCED PLASTIC STAPLE BUTTON

Forrest G. Purinton, Waterbury, Conn., assignor
to The Patent Button Company, Waterbury,
Conn., a corporation of Connecticut

Application October 23, 1940, Serial No. 362,447

6 Claims. (Cl. 24—95)

My invention relates to new and useful improvements in reinforced plastic staple buttons.

One of the principal objects of the invention is to provide a reinforced plastic button consisting of a plastic body or head, in which there is embedded a plate having insignia thereon, the top surface of which insignia is preferably to lie flush with the face of the button. Thus, by embedding the name plate, it calls for only one name die to make up these plates rather than cutting the insignia in all the cavities in a multiple cavity die.

A further object of the invention is to provide a button back or shell to reinforce the pre-molded plastic insert and to further provide an anvil which is to be deposited in the hub of the shell, after which the pre-molded plastic body is fitted within the shell and the shell rolled to thus provide a staple button which will be relatively inexpensive to manufacture, pleasing in appearance, and efficient in service.

Still another object of the invention is to provide a button consisting of a shell, the bottom of which is imperforate but provided with a depressed central ring or groove to properly space the prongs of a staple fastener, which, in turn, are to pass through the shell and impinge and be deformed on an anvil within the shell. Above the anvil is a pre-molded plastic button head, in which is preferably embedded the desired insignia.

Still another object of the invention is to provide a reinforced plastic button wherein the conventional forms of shells may be used, in which shells are to be deposited, first, an anvil and, then, a pre-molded plastic button head, which latter, in turn, has firmly embedded therein a plate, on which the desired insignia appears and which insignia will lie flush with the outer surface of the plastic button head.

Still another object of the invention is to provide a simple and efficient reinforced plastic button which is provided with an anvil for deforming the prongs of a staple fastener and wherein the body of the button may be of plastic, the edge of which is framed within the button back or shell.

With these and other objects in view, the invention consists in certain new and novel arrangements and combination of parts, as will be hereinafter more fully described and pointed out in the claims.

Referring now to the drawing showing a preferred embodiment,

Fig. 1 is an enlarged top plan view of the completed button;

Fig. 2 is a vertical sectional view on the line 2—2 of Fig. 1;

Fig. 3 is a top plan view of the insignia plate;

Fig. 4 is a sectional view taken on the line 4—4 of Fig. 3;

Fig. 5 is a view of the anvil taken on the line 5—5 of Fig. 2;

Fig. 6 is a detail of a staple fastening member;

Fig. 7 is a fragmentary enlarged bottom view 5 of the shell; and

Fig. 8 is a fragmentary detail of the center of the shell, as shown in Fig. 7.

Referring now more particularly to the several views, and for the moment to Fig. 4, there is 10 shown what I term the insignia plate 1, which is preferably made of relatively thin sheet metal stamped to dome shape and also has stamped therein the insignia in the form of raised letters 2. In the present instance, I have shown the 15 letters "P. B. Co," although it will be understood that any brand or trade-mark or other design may be stamped in this plate.

The plate preferably has a rim 3, about its periphery, while the plate proper is provided with 20 the small prick-point openings 4 between and adjacent the letters and the further prick-point openings 5 within the islands of the letters, as may be seen in Figs. 3 and 4.

The plastic body or head of the button is 25 formed by placing the plate 1 in an inverted position from that shown in Fig. 4 in a die cavity (not shown), on which is deposited a Bakelite or plastic pill. The mold is then closed and heated, so that the plastic will form the body or head 6 of the button and will also be forced through the 30 said openings 4 and 5 to fill up the spaces between the letters and the spaces within the letters and thus cover or embed the plate but leave the outer surfaces of the letters flush with the 35 face of the button.

In this manner, the plate is well embedded and the plastic above the plate is well anchored with its body.

Likewise, the islands or enclosed spaces within 40 the letters are also well anchored to the base and will not fall or drop or work loose from their confined positions.

The openings 4 and 5 above-mentioned thus 45 form passageways through the plate for the Bakelite when the latter is in its plastic form and cause the plastic above the plate to be well anchored with the plastic body.

The button is provided with the hub 7, while 50 in the bottom of the hub is the central arcuate portion 8 to conform to the central contour of a metal anvil 9, as may be seen in Figs. 2 and 5. This anvil is circular in outline and has the dome-shaped center 10 and the narrow peripheral 55 rim 11.

The pre-molded plastic insert is forced in the 60 button back or shell 12, which latter is provided with the upper peripheral flange 13, which flange is to be rolled, as shown in Fig. 2, and contact about the rim 3 of the plate 1, which plate,

it is to be remembered, is embedded in the body 6 of the plastic button.

It will be understood that if desired the plastic material forming the body or head 6 may extend to the outer peripheral edge of the rim of the button and then the flange or rolled rim 13 would contact on the upper surface of the plastic, but I have illustrated, as may be seen in Fig. 2, the rolled rim contacting with the metal rim of the plate 1, which is the preferred form.

When the pre-molded plastic body of the button is forced down into its shell, the lower surface of the plastic hub will bear tightly against and back up the anvil 9 heretofore mentioned, so that when the button is being attached, the attaching pressure from the plunger (not shown) will be transferred to the anvil and thus drive the prongs of the staple, about to be mentioned, through the cloth and against this anvil plate.

The shell 12 has a depressed ring 14 formed in its under surface, which may well be seen in Figs. 2, 7, and 8, which leaves the small central inverted dome portion 15. The diameter of the dome and ring is such that the dome will extend between the prongs 16 of a staple fastener 17, so that the points of the prongs, during the attaching operation, will be held in a properly spaced position. The prongs, in an attaching operation, will pierce the metal of the ring 14 and, of course, will impinge against the central arcuate portion 18 of the anvil 9 and be deformed and bent to a position like that shown in Fig. 2 to thus firmly hold the button to its cloth 19.

After the prongs of the staple are once deformed, the button cannot be removed or detached without tearing the cloth or destroying the button.

From the foregoing, it will be seen that I have provided a relatively inexpensive staple button wherein, if desired, insignia may be embedded in a plastic body and wherein an anvil is to be dropped into the button back or shell, after which the pre-molded body is forced within the button shell and the flange of the button shell rolled to tightly hold the plastic body within the shell.

It will be seen that the anvil is held tightly in position in the bottom of the shell by the plastic body, and the anvil being of a relatively hard metal will deform the prongs and jam them against the inner surface of the button shell to thus tightly hold the button in its attached position.

Buttons of this type are generally assembled in what is known as a dial press, so that it is a simple matter to drop or deposit the anvil in the shell previous to the fitting of the pre-molded plastic body in the shell.

It will be understood that although I prefer to utilize the anvil for turning the prongs of the tack, it is conceivable that a button could be made wherein the plastic would be so hard when in its final molded condition that it might turn and deform the prongs of the staple. It, therefore, may be possible to dispense with the anvil in some cases and I do not wish to be limited to the inclusion of the anvil.

Furthermore, by pre-molding the plastic body with the insignia thereon, the entire operations necessary in assembling the button are reduced to a minimum.

Many slight changes might be made without departing from the spirit and scope of the invention.

Having thus described my invention, what I claim as new and desire to secure by Letters Patent is:

1. A reinforced plastic button consisting of a metal shell, a pre-molded plastic insert within the shell, the insert provided with a hub adapted to deflect the prongs of a staple fastener, and the shell secured about the peripheral rim of the plastic insert.

2. A button consisting of a shell, an anvil located in the bottom of said shell, a pre-molded plastic insert within the shell, the insert having a hub bearing against said anvil, and the shell secured about the peripheral rim of the plastic insert.

3. A reinforced plastic button consisting of a metal body shell, a molded plastic insert within the shell, the bottom of the insert having a central arcuate portion, a perforated metal plate having projections and depressions formed therein and embedded slightly below the surface in said plastic insert, the said plate slightly projecting beyond the marginal edge of the top surface of the plastic insert to form a rim, and the upper edge of the body shell secured to said marginal rim to tightly hold the plastic insert down within the body shell.

4. A reinforced plastic button consisting of a metal body shell, a pre-molded plastic insert within the shell, the bottom of the insert having a central arcuate portion adapted to deflect the prongs of a staple fastener during an attaching operation, a plate having raised portions thereon embedded within the plastic insert and said plate providing a marginal flange circumferentially of the top surface of the plastic insert, and the upper edge of the body shell crimped about said flange to tightly hold the plastic insert within the body shell.

5. A reinforced plastic staple button consisting of a body shell having an imperforate hub, an anvil resting in the bottom of the shell, a pre-molded plastic insert fitted within the shell, a metal plate embedded slightly below the surface of the plastic insert and portions of the plate visible from the face of the insert, the bottom of said plastic insert bearing against said anvil, and the upper peripheral edge of the body shell secured about the peripheral edge of said plate to tightly hold the plastic insert and anvil down within said hub of the body shell.

6. A staple button consisting of a metal body shell, an anvil located in the bottom of the shell, the said bottom of the shell being imperforate and having a depressed ring portion formed therein to properly guide the prongs of the staple when piercing said shell, a pre-molded plastic insert within the shell and bearing against said anvil, a perforated plate having raised portions embedded slightly below the surface of the plastic insert, and the upper edge of the body shell crimped about the peripheral edge of said embedded plate to hold the plastic insert and the anvil tightly against the ring portion formed in the bottom of the said hub.

FORREST G. PURINTON.
